UNITED STATES PATENT OFFICE.

JOSEPH T. ROBBINS, OF NEWTON, IOWA.

APPARATUS FOR GENERATING STEAM AND DESTROYING AND UTILIZING GARBAGE, &c.

SPECIFICATION forming part of Letters Patent No. 645,131, dated March 13, 1900.

Application filed June 29, 1891. Serial No. 397,769. (No model.)

To all whom it may concern:

Be it known that I, JOSEPH T. ROBBINS, M. D., a citizen of the United States of America, residing at Newton, in the county of Jasper 5 and State of Iowa, have invented a new and useful Apparatus for Generating Steam and Destroying and Utilizing Garbage, &c., of which the following is a specification.

My object is to provide a furnace adapted 10 for burning bituminous coal, garbage, dead animals, night-soil, &c., without allowing offensive fumes to escape, to facilitate the removal and destruction of offensive waste matter in buildings, towns, and cities, to generate heat and steam, and to economize fuel in operating a furnace.

My invention consists in the arrangement, combination, and operation of a boiler, a series of boiler-tubes, two furnace-grates, two 20 bridge-walls, a steam superheater and distributor, and a fuel-magazine, as hereinafter set forth, pointed out in the claims, and illustrated in the accompanying drawings, in which—

25 Figure 1 is a vertical and longitudinal sectional view clearly showing the relative positions of the various parts, and Fig. 2 is a transverse sectional view on the line *x* *x* indicated in Fig. 1.

30 *A* represents a grate located at the bottom and front portion of the complete furnace.

*A*² is a door in the front wall, through which access is gained to the combustion-chamber above the grate *A*, and *A*³ is a door in the 35 same wall leading to the ash-pit under the grate *A*.

*A*⁴ is a door through which access is gained to the upper fire-chamber and upper grate.

30 *B* is a bridge-wall at the rear end of the grate *A*. It rises above the grate and extends upward and rearward. Its top is inclined.

*B*² is a vertical extension on top of the wall *B*, preferably made of metal and adapted to 45 support tubes and to deflect the products of combustion.

C is a horizontal boiler supported above the top of the bridge-wall in such a manner that the products of combustion rising from the 50 grate and combustion-chamber in front of the bridge-wall will be directed by the bridge-wall and its extension to envelop the boiler.

D and *D*² are hollow frames or boiler-sections fixed to the bottom and end portions of the boiler *C*. 55

*D*³ is a hollow frame or boiler-section fixed to the front wall of the furnace.

1 2 3 4 represent a series of tubes connected with the sections *D*, *D*², and *D*³ as required to establish communication with each other 60 and the boiler *C* and to circulate water and steam.

F are grate-bars fitted to the upper row of the tubes in such a manner that air can circulate between the top surfaces of the tubes 65 and the under surface of the grate-bars. For this purpose each bar in this second grate has a longitudinal groove *g* in its bottom and transverse grooves *h* intersecting the groove *g*.

J are perforated tubes extended through 70 the front wall of the furnace and between the tubes of the sectional boiler to the rear portion of the grate-bars *F* and perforated as required to convey and heat and distribute air and to mingle oxygen with the products of 75 combustion between the two grates for the purpose of promoting combustion and increasing heat.

K is a second bridge-wall extending up from the hollow frame *D*² and front portion of the 80 boiler *C* to the roof of the furnace as required to direct the products of combustion from the fuel and chamber above the upper grate downward through the upper grate to mingle with the products of combustion rising 85 from the lower grate and to envelop the series of tubes and boiler-sections 1 2 3 4 as they pass around the bottom of the hollow frame and boiler-section *D*² and the deflector extending downward and up between the sections *B*² and *D*² to envelop the boiler *C* in passing around the boiler-section *D* toward the escape-flue *L*. A damper *K*² in the wall *K* can be opened when the door *A*⁴ is to be 90 opened to allow a direct backward draft. 95

M is a steam superheater and distributor connected with the boiler *C* in such a manner that it will discharge its contents downward over and through the fuel on the upper grate to aid in promoting combustion. 100

N is a fuel-magazine suspended from the roof of the furnace in such a manner that its contents can be discharged therefrom to lodge upon the upper grate. It has an air-tight

cover and a pivoted bottom P and a crank-handle R connected therewith in such a manner that the bottom can be turned as required to dump fuel from the magazine to drop upon 5 the upper grate.

In the practical operation of my invention I start fires on the lower and upper grates when the boiler is supplied with water. The fuel may be introduced through the doors in 10 the front wall or through the fuel-magazine. When I wish to cremate and destroy garbage or other offensive and waste material, I place such matter in the magazine and then subject the matter therein to the heat that rises 15 and envelops the magazine until it is dried and ready to be dumped upon the fuel and fire on the upper grate, where it will be charred and burned. Particles that fall through the upper grate will lodge on the 20 lower grate, and the odors and fumes of the burning matter will be destroyed by the fire on the upper and lower grates. The hydrogen gas discharged and distributed from the steam-superheater M and the oxygen con- 25 veied and heated by the tube J will unite with the products of combustion liberated from the carbonaceous substances on the grates and produce a combustible gas which will burn readily and make an intense heat 30 at a reduced expenditure of time, because the garbage and other offensive waste matter are utilized in producing heat and steam and consequently the quantity of coal and other valuable fuel consumed is reduced.

35 I claim as my invention—

1. In a furnace, a closed chamber, a grate in the bottom of the chamber, a magazine supported in the chamber and over the grate, a deflector extending downward at the rear end 40 of the grate, a series of boiler-tubes under the grate, and a second grate under the sectional boiler arranged and combined as and for the purposes stated.

2. In a furnace, a horizontal grate at the 45 bottom and front portion of a furnace-wall, a series of boiler-tubes supported above said grate, a second grate supported over the said boiler-tubes, a closed chamber above the said upper grate, and an air superheater and distributor under the upper grate, arranged and combined to operate in the manner set forth for the purposes stated.

3. In a furnace, a horizontal grate at the 55 bottom and front portion of a furnace-wall, a series of boiler-tubes supported above said grate, a second grate supported over the said boiler-tubes and a closed chamber above the said upper grate, an air-superheater under said upper grate, and a steam superheater 60 and distributor above the upper grate, arranged and combined to operate in the manner set forth for the purposes stated.

4. An apparatus for generating steam, and destroying and utilizing garbage, &c., comprising a furnace-wall, a grate extending rear- 65 ward from the front and lower portion of the wall, a bridge at the rear end of the grate extending backward and upward therefrom, a series of boiler-tubes above the said grate and said bridge-wall, a second grate above 70 the front portion of the said boiler-tubes, a closed chamber above the upper grate, a magazine supported in said chamber and above the upper grate and a boiler in rear of said closed chamber communicating with the said 75 boiler-tubes, a steam superheater and distributor above the upper grate and an air superheater and distributor under the upper grate, all arranged and combined to operate in the manner set forth for the purposes 80 stated.

5. In an apparatus for generating steam and destroying and utilizing garbage, &c., a furnace-chamber having a grate in its bottom and closed above the grate to direct the products of combustion down through the grate, a magazine supported from the closed top of the chamber and over the grate and provided with a cover and a pivoted bottom and means for operating the bottom, a deflector at the 90 rear end of the grate, tubes for generating steam located under the grate and a second grate located under the said tubes, an opening in rear of the lower grate and under the deflector projecting down in rear of the upper grate for the rearward discharge of the 95 products of combustion liberated from fuel on the two grates, and means for admitting air to the fuel on the grates, arranged and combined to operate in the manner set forth 100 for the purposes stated.

6. In a furnace, a chamber having a grate situated near its center, a grate in its lower portion and an opening for the discharge of products of combustion in its rear wall be- 105 tween the two grates the upper grate having means for supplying air to support combustion thereat, and to permit of a downdraft therethrough and the lower grate having means for feeding air below the same so as 110 to permit of an updraft of the air between the bars.

7. In a downdraft-furnace, the combination of an air conveyer, superheater and distributor with a grate and means for directing the 115 products of combustion downward through the grate to mingle with the hot air distributed immediately under the grate by the said conveyer superheater and distributor located under the grate for the purposes stated.

JOSEPH T. ROBBINS.
